UNITED STATES PATENT OFFICE.

JAMES A. DITTEMORE, OF ST. JOSEPH, MISSOURI.

GUN-SIGHT.

1,256,987.

Specification of Letters Patent. Patented Feb. 19, 1918.

Application filed December 5, 1916. Serial No. 135,146.

To all whom it may concern:

Be it known that I, JAMES A. DITTEMORE, a citizen of the United States, residing at St. Joseph, in the county of Buchanan, State of Missouri, have invented certain new and useful Improvements in Gun-Sights; and I do hereby declare the following to be a full, clear, and exact description of the invention, such as will enable others skilled in the art 10 to which it appertains to make and use the same.

This invention relates to gun sights.

The object of the invention is to provide a gun sight, which, in principle may be used 15 upon guns of large or small caliber, and which permits the covering of the target without losing the vision of the entire target.

A further object of the invention is to provide a gun sight which may be used with 20 equal facility either in daylight or darkness. To this end, I have constructed a sight which involves the use of both eyes in sighting the gun or rifle, and the alining of two intermediate points with the target within 25 the vision of one eye.

With the above objects in view and such others relating to the particular construction of the device as may hereinafter appear, my invention will now be fully set forth and 30 described, reference being had to the accompanying drawings.

In the drawings:—

Figure 1 is a longitudinal section through the sight,

Fig. 2 is a section on line 2—2 of Fig. 1,
Fig. 3 is a section on line 3—3 of Fig. 1, and

Fig. 4 is a diagram illustrating the principle upon which my invention is based.

Referring more particularly to the drawings, 1 indicates a metal tube of suitable length and diameter which is mounted upon a rifle or gun barrel along the line of sight. The front end of the tube 1 is closed by an opaque diaphragm 2 so that the vision does not pass therethrough. A comparatively short distance behind the opaque diaphragm 2 is mounted a second diaphragm 3 which thereby sub-divides a small chamber 4 at the 50 front end of the tube 1. The diaphragm 3, as shown in Fig. 3, has formed in its upper portion, or on its edges, a sight opening 5, the sight opening 5 being in the line of sight of the gun. Alined with the opening 5 is a 55 sight opening 6 similarly formed in a diaphragm 7 which closes the rear end of the

tube 1. As shown in Fig. 2, the opening 6 is of smaller diameter than the opening 5.

Mounted within the chamber 4 is a light source 8 which may be a small electric light, 60 a phosphorescent or other luminous point, or any other radiant element which will faintly illuminate the opening 5 in the diaphragm 3. In order to cut down the luminosity, and also to provide a contrasting illuminated point, the opening 5 may be covered with a transparent diaphragm 9 of red or other suitably colored material. By this arrangement, when the sight is used in the daytime, the red or other contrasting light 70 point may be readily distinguished from the sunlight.

The construction of the above described sight follows the principle, that, if the eyes are focused on a distant object, as, *a* in Fig. 75 4, and an object *b* is held in the line of vision between one eye and the object *a*, the object *b* apparently does not obstruct the vision, or, in other words, apparently one sees through the object *b*. Also, if a third object *c* is placed in the line of vision between *b* and *a*, there is likewise no apparent obstruction of the vision. Apparently, then the object *a* is seen through the objects *b* and *c*, and if with both eyes on the object *a* as a 85 target, the objects *b* and *c* are used as the sight elements on a gun, it is apparent that when the objects *b* and *c* are alined between the target or object *a* and one eye, the gun must be directly trained upon the target. 90 Substituting now, the opening 6 for the object *b* and the luminous opening 5 for the object *c*, it is evident that when one eye is kept upon the target, and the other eye keeps in vision the red spot of light within the tube 95 1, and the gun is manipulated until the red spot centers upon the target, the gun will be sighted or trained upon the latter.

In this manner, a very accurate, and a dependable sight is provided for use either 100 in the daytime or at night when it is only possible to outline the target. The illuminated opening 5 not only renders the sight visible but constitutes one of the sight elements, and obviously, the luminous point 105 cannot be seen without alining the opening 6 with the eye. When this is done, and the gun manipulated until the light centers upon the object to be fired at, the gun must thus, of necessity stand in sighted position. 110

What I claim as my invention is:—

1. A gun sight, comprising in combina-

tion, a tube having an illuminated chamber at its forward end, having a pair of diaphragms provided with openings on a line parallel to the axis of the tube, and means in the axis of the tube for illuminating the forward opening.

2. A gun sight, comprising in combination, a tube having its forward end closed, a diaphragm at the rear end of the tube provided with a sight opening, an intermediate diaphragm transversely arranged in the tube and provided with an opening, said diaphragms being so arranged that a line joining the centers of said openings lies parallel to the axis of the tube, and means for illuminating the second opening.

3. A gun sight, comprising in combination, a tube having its forward end closed, a diaphragm at the rear end of the tube and having an opening formed therein, an intermediate diaphragm transversely arranged to the tube and forming with the closed end thereof a light chamber, said intermediate diaphragm having an opening, said diaphragms being so arranged that a line joining the centers of said openings lies parallel to the axis of the tube, and a light source

in the light chamber for illuminating the second opening.

4. A gun sight, comprising in combination, 30 a tube having its forward end closed, a diaphragm at the rear end of the tube, an intermediate diaphragm near the front end of the tube, and forming an illuminating chamber with the closed end of the tube, 35 said diaphragms having openings in a line parallel to the axis of the tube, and means for illuminating the opening in the intermediate diaphragm.

5. A gun sight, comprising in combination, 40 a tube having a closed end, a diaphragm at the rear end of the tube, a forward diaphragm forming an illuminating chamber with the closed end, said diaphragms having openings on a line parallel 45 to the axis of the tube, the opening in the forward diaphragm being illuminated from the front of the latter.

In testimony whereof, I affix my signature, in the presence of two witnesses.

JAMES A. DITTEMORE.
